FURNITURE SPRING STRUCTURE

Robert C. Heimerdinger, Chicago, Ill., assignor to
 Greggory, Inc., Chicago, Ill., a corporation of
 Illinois

Application October 30, 1942, Serial No. 463,878

4 Claims. (Cl. 155—179)

The present invention relates to furniture such as chairs, sofas, davenports, beds, cots and similar structures upon which persons may dispose themselves in various positions. More particularly this invention concerns a spring structure which is adapted for a variety of types of furniture and is capable of yieldably sustaining the weight of the person or persons occupying the chair, davenport, or other article of furniture.

The main objects of this invention are to provide an improved spring structure that is capable of installation and use in any of a large variety of articles of furniture, and particularly as a substitute for coiled springs in supporting upholstery; to provide an improved spring structure for furniture and the like, which almost completely eliminates the need for metal in its composition; and to provide an improved spring structure of this kind which can be made almost wholly of fibrous material.

A preferred embodiment of the invention is illustrated in the accompanying drawing in which:

Figure 1 is a fragmentary view in perspective of an end or side portion of the frame for a chair, davenport, or the like, showing examples of the novel spring structures incorporated in the seat and back thereof.

Fig. 2 is a detail in perspective with parts broken away, of a sheet of laminated fibrous material of suitable composition to be adapted for forming or shaping it into the spring structure elements contemplated herein.

Fig. 3 is an edge view of a unit spring structure and portions of the supporting frame showing a preferred form of the spring for use in the seat of the furniture article.

Fig. 4 is a view similar to Fig. 3 showing the manner in which the spring elements may yield when subjected to the weight of an occupant seated thereon.

Fig. 5 is a detail plan, illustrating a suitable arrangement of the seat spring unit in an elongated article of furniture such as a davenport, settee, or the like.

Fig. 6 is a detail in side elevation, of an arrangement of cooperating spring elements in the back rest of an article of furniture.

The drawing is to be understood as being more or less schematic for the purpose of disclosing a typical or preferred embodiment of this invention.

The material from which the spring structure is fabricated is a laminated sheet preferably comprising alternating layers or plies A, B and C of fibrous materials adhesively secured together as an integral board or plate. In a preferred form there are three plies, the central ply or core A being of wood with its grain transverse to the length of the sheet and the outer plies B and C being of fabric such as woven threads or tough cylinder kraft paper with its grain disposed

lengthwise of the sheets. The wood veneer is of the well-known type that is formed by slicing a continuous ribbon from the periphery of a log rotated on a longitudinal axis in a lathe. The 5 kraft paper is preferably the type known as cylinder kraft wherein the grain is characterized by relatively long fibers. In assembling the three plies above-mentioned, it is desirable that the grain of the veneer ply A be disposed transversely of the strip or substantially at right angles to the long fibers of the kraft paper facing plies B—C, in the manner indicated in Fig. 2. The material of the spring, prior to being shaped, is preferably an elongated rectangular member with the long fibers of the outer ply kraft paper or other materials disposed lengthwise of the strip and with the grain of the veneer disposed in the direction of the width of the strip.

The frame of the article of furniture shown 10 in Fig. 1, comprises longitudinally disposed front and rear rails 10 and 11, respectively, that are joined at their ends by transverse end rails 12 to form a rectangular open frame. Uprights 13 rise from the forward or front corners of this 15 open frame and backwardly curved uprights 14 rise from the rear corners of said frame. These latter uprights 13 and 14 and their connecting cross bars 15 and 16 are variously shaped to conform to the requirements of any particular 20 design of the finished article.

An elongated horizontally disposed rail 17 extends between and is connected at its ends to the upper portions of the rear uprights 14, and another or lower rail 18, parallel with rail 17, 25 extends between and is connected at its ends to the rear uprights 14. These rear uprights 14 and the horizontal connecting rails 17 and 18 form an open rectangular frame for the back member of the article of furniture, just as the 30 front and rear rails 10 and 11 and the end rails 12 form an open frame for the seat member of the article.

The horizontal rails 17 and 18 of the back member are joined by relatively narrow spring 45 members 19 of the fibrous material which has been hereinbefore described. These strips 19 are arranged side by side in spaced relation to each other, as shown in Fig. 1, with their ends connected to the respective rails in a suitable manner. Prior to assembly with the back frame, the laminated strips 19 are shaped and treated by a suitable process to give them a permanent form-retaining "set" with at least one looped end. As shown in Figure 1, the major portion 50 of a strip 19 is provided with a forwardly convex bow and the upper end portion is more sharply curved to form a relatively wide open loop bend 20 which terminates in a straight terminal portion 21 to fit flat against the rear face of the 55 upper rail 19 of the back frame to which it is secured.

The loop bend 20 is arched up forwardly from the back rail 17 so that the bowed body portion is spaced from said rail and is free to flex for comfortable support of the occupant's back.

One or more strips 19.1 of suitable flexible material may be woven across the medial portions of the spring members 19. These strips 19.1 may be of a suitable webbing or tape, or they may be lengths of the same laminated fibrous material, and they are laced alternately in front of and back of the successive spring members 19.

In the form shown in Fig. 1, a group of three of the members 19 would occupy a space approximately corresponding to a seating unit space for an adult person and the middle member of such group in a chair and the corresponding alternate members in a davenport are each reinforced by a supplemental spring member 19.2 mounted as shown in Fig. 6. The member 19.2 is more sharply curved than the corresponding member 19 so as to reinforce the latter mainly at the region where the occupant is likely to apply the greatest amount of pressure.

The seat structure is supported upon parallel slats 22, extending between the end rails 12, and spaced inward of the front and rear rails 10 and 11.

Mounted on the slats 22 are a series of similarly formed seat spring units, each comprising as illustrated in Figures 1, 3 and 4 an S-shaped member 23 having reversely curved open loops 24 at its opposite ends and a seat plate member 25 overlying the S-shaped member 23 and spanning the space between the loops 24. These spring structure units are preferably of a width such that two of them placed side by side and spaced apart will occupy a unit-seating space for an adult person.

With three-ply material, such as is illustrated in Fig. 2, it is found that the spring members 23 will have sufficient strength, if made up of two strips of the laminated material laid one upon the other.

A single strip of the material will serve for the seat plate member 25 in a chair but for a davenport, the strips 25 may be either single or double but it is preferred that at least the outermost ones of the series—that is those which are adjacent the arms of the davenport—should be stiffer than the intermediate ones so as to tend to prevent the occupant of the end-seating section from being tipped toward the side arms.

The seat plate members 25 preferably extend forward and back sufficiently far enough to overhang the loops 24, as illustrated, and the front edge of each seat plate is reinforced by a wooden cleat 26 which preferably is in such position as to overlie the front rail 10 so as to engage the latter and serve as a limit stop for the yielding of the spring structure under excessive strain, such as might happen if a person should step upon and place his entire weight near the front edge of the seat.

In the form shown, the seat plates are fastened to the S-shaped members by screws 27 which pass through perforations in the laminated sheets and engage cleats 28. Similarly, screws 29 and cleats 30 are used to fasten the lower portions of the loops 24 to the slats 22.

The cleats 28 and 30 are preferably of a length corresponding to the width of each unit spring structure but the reinforcement 26 is preferably a bar of wood that extends throughout the series of seat members and holds their front edges normally in alignment with each other. A similar

bar 31 ties the seat members together at a point in front of the rearward loops 24 and accordingly extends throughout the length of the series.

Although but one specific embodiment of the invention is herein shown and described, it will be understood that numerous details may be altered or omitted without departing from the spirit of the invention as defined by the following claims.

10 I claim:

1. A furniture spring structure comprising superposed members of laminated material, each member comprising a plurality of plies of fibrous sheet material integrally united to each other, the said superposed members being permanently bent in longitudinal vertical section to an S-shape disposed generally in a horizontal direction, cleats extending along the terminal transverse end edges of said loops adapted to unite the superposed members for simultaneous flexing movement, other superposed members of laminated fibrous material constituting a body support overlying and secured to upper portions of the aforesaid S-shaped element adjacent the loops thereof, and means anchoring the lower portions of the loops of said S-shaped element to a furniture frame.

2. The combination with a rigid frame comprising a pair of fixed parallel horizontal bars, of a spring element comprising a plurality of plies of fibrous sheet material integrally united to each other and permanently set to S-shape and secured crosswise to both said bars so as to form an upward bowed U-shaped end portion and a downwardly bowed U-shaped end portion with an inclined intermediate portion connecting the upper limb of one U-shaped portion to the lower limb of the other U-shaped portion, and a seat plate above said spring element and fixed thereto at the upper limbs of said U-shaped portions.

3. The combination with a rigid frame comprising a pair of fixed parallel horizontal bars, of a spring element comprising a plurality of plies of fibrous sheet material integrally united to each other and permanently set to S-shape and secured crosswise to both said bars so as to form an upward bowed U-shaped end portion and a downwardly bowed U-shaped end portion with an inclined intermediate portion connecting the upper limb of one U-shaped portion to the lower limb of the other U-shaped portion, and a seat plate above said spring element and fixed thereto at the upper limbs of said U-shaped portions, said seat plate extending beyond the U-shaped portion at one end, and said frame having abutment means positioned to be engaged by and limit the downward movement of said seat extension.

4. The combination with a rigid frame comprising a pair of fixed parallel horizontal bars, of a plurality of spring elements, each comprising a plurality of plies of fibrous sheet material integrally united to each other and permanently set to S-shape and secured crosswise to both said bars so as to form an upward bowed U-shaped end portion and a downwardly bowed U-shaped end portion with an inclined intermediate portion connecting the upper limb of one U-shaped portion to the lower limb of the other U-shaped portion, an individual resilient flexible seat plate above each said spring element respectively and fixed thereto at the upper limbs of said U-shaped portion, and a cleat parallel to said first-named bars and respectively fixed to each said seat plates to tie the latter together.

ROBERT C. HEIMERDINGER.
